Mr. Attorney.

UNITED STATES PATENT OFFICE.

CLARENCE DENTON TUSKA, OF HARTFORD, CONNECTICUT, ASSIGNOR TO THE C. D. TUSKA COMPANY, OF HARTFORD, CONNECTICUT, A CORPORATION OF CONNECTICUT.

VARIOMETER COIL AND METHOD OF MAKING SAME.

Application filed April 2, 1921. Serial No. 458,011.

To all whom it may concern:

Be it known that I, CLARENCE D. TUSKA, a citizen of the United States, and resident of Hartford, county of Hartford, State of Connecticut, have invented certain new and useful Improvements in Variometer Coils and Methods of Making Same, of which the following is a specification.

This invention relates to an electric instrument for use in varying or changing the characteristics of an electric current. A device of this sort finds particular adaptability in the art of wireless where it may be employed to vary the wave length of transmitting or receiving apparatus, or for other purposes.

The aim of the invention is to provide an electrical instrument having various features of novelty and advantage and which is particularly characterized by its simplicity and economy in construction, its neatness in appearance and its effectiveness in operation. The invention is also concerned with the method of securing a coil of insulated wire to a body of insulating material.

In the accompanying drawings—

Fig. 1 is an elevational view, with parts in section, of an improved variometer constructed in accordance with the present invention.

Fig. 2 is taken on line 2—2 of Fig. 1.

Fig. 3 is a diagrammatic view of the wiring and

Fig. 4 is a view illustrating the method of incorporating a coil of wire in the surface of a body of insulating material.

Referring to the drawings in detail, *a* denotes generally the stator body comprising two blocks 10, 10 of insulating material secured together by bolts 11. This body has an opening therethrough which is in the form of a central zone of a sphere. Applied to the walls of this opening is a stator winding *b* formed of two coils, one in each block 10.

The letter *c* denotes a rotor body of insulating material and having a spherical perimeter to which is applied a coil or winding *d*. The rotor is supported at diametrically opposite points by the trunnions 13 having bearings in sleeves 14, 14' mounted in registering notches 15 in the abutting faces of the blocks 10. On one of these trunnions is fixed a knob 16 by means of which the rotor

may be angularly adjusted to change the relation of the stator and rotor windings and thus affect the current passing through these windings. For the purpose of holding the rotor in any position of adjustment and to assure a low resistance connection, springs 17 are mounted on the trunnions for frictional engagement with the sleeve 14 and the nuts 18.

Two of the bolts 11, in addition to tying the blocks 10 together, serve as binding posts through which the current is led to and from the windings. In the present instance, one end of the stator winding *b* is connected to the upper right hand post 11 (referring to Fig. 1) and the other end is connected to the right hand sleeve 14'. The opposite ends of the rotor winding *d* are respectively connected to the trunnions 13, and the sleeve 14 is connected by means of a wire 20 to the upper left hand bolt 11. One of the abutting faces of the blocks 10 is grooved or recessed as at 21 to accommodate the wires leading from the binding posts 11 to the windings.

The present invention provides an improved method for securing the stator coils to the blocks 10, and this method will now be described with reference to Fig. 4.

The wires forming the stator coils are, by preference, covered with a suitable insulating material or fabric, such as cotton. The wire is formed into a coil of the proper shape and size by winding it onto a form (not shown) having a surface which is complementary to that of the opening in each block *b*. This form will be similar to the holder 25. An insulating material such as a gum may then be applied to the coil to hold the several convolutions thereof in position and then the coil is transferred from the form to the holder which is positioned within a mold 26. If desired, the form may be dispensed with and the wire coiled directly on the holder 25. The mold is filled with an insulating material in a plastic state and preferably this material has a melting point which is not greater than that of the insulating material applied to the coil. Pressure is applied to the insulating material, as by means of the plungers 27, to closely compact it about the coil on the holder, and then the insulating material is permitted to solidify or set. The block of

2
insulating material, together with the coil embedded in the surface thereof, may now be removed from the mold. By proceeding in accordance with the method just described, the stator coil becomes partly embedded in the surface of the insulating material and the insulating material unites, so to speak with the cotton covering of the wire so that the convolutions of the coil are very tightly held in place, and will not become loosened or disarranged even under the rather rough usage to which variometers are frequently subjected.

It is of course obvious that the invention is susceptible of various modifications and changes which are within the spirit of the invention without departing from the scope of the following claims, it being understood that the present disclosure of the invention is by way of illustration only and it is not to be taken as restrictive of my conception.

I claim as my invention:—

1. That improvement in the art herein described which consists in forming a cavo-convex coil of wire, applying the coil to a holder within a mold, filling the mold with an insulating material in a plastic state, applying pressure to said insulating material, allowing said material to solidify, and then removing the block of insulating material together with the coil embedded in the surface thereof from said holder.

2. That improvement in the art herein described which consists in forming a coil of insulating wire, applying an insulating material to the coil to hold the convolutions thereof in position, applying the coil to a holder within a mold, filling the mold with an insulating material in a plastic state, applying pressure to said insulating material, allowing said material to solidify, and then removing the block of insulating material together with the coil embedded in the surface thereof from said holder.

45 3. That improvement in the art herein described which consists in forming a coil of insulating wire, applying a gum to the coil to hold the convolutions thereof in position, applying the coil to the holder within a mold, filling the mold with an insulating material whose melting point is not greater than that of the gum, applying pressure to said insulating material, allowing said material to solidify, and then removing the block of insulating material together with the coil embedded in the surface thereof from said holder and mold.

4. That improvement in the art herein described which consists in forming a coil of insulating wire by winding the wire about a form the perimeter of which is parti-spherical in shape, applying a gum to the coil to hold the convolutions thereof in position, transferring the coil from the form to a holder of like shape and size as said form and positioned within a mold, filling the mold with an insulating material whose melting point is not greater than that of the gum, applying pressure to said material to compact it about the coil, permitting said material to solidify, and then removing the insulating material together with the coil embedded in the surface thereof from the mold and holder.

5. That improvement in the art herein described which consists in applying a coil of fabric-covered wire in the form of a section of a sphere to a convex holder within a mold, filling the mold with the insulating material in a plastic state, applying pressure to said insulating material, allowing said material to solidify, and then removing the block of insulating material together with the coil embedded in its concave surface from said holder.

6. That improvement in the art herein described which consists in forming a parti-spherical coil of insulating wire, applying insulating material to the coil to hold the convolutions thereof in position, applying the coil to a convex holder within a mold, filling the mold with an insulating material in a plastic state, applying pressure to said insulating material, allowing said material to solidify and then removing the block of insulating material together with a coil embedded in the concave surface thereof from said holder.

7. In a device of the character described, a block of insulating material provided with a concave opening, and a coil of fabric covered wire embedded in the walls of the opening of said block with the material of the block united with the fabric about said wire.

8. In a device of the character described, a block of relatively hard insulating material provided with a parti-spherical opening, and a parti-spherical coil of fabric covered wire embedded in the walls of said opening with the material of the block united with the fabric about said wire.

CLARENCE DENTON TUSKA.
